UNITED STATES PATENT OFFICE.

HENRY BREHMER, OF NEW YORK, N. Y., ASSIGNOR TO BURR DAUCHY, OF SAME PLACE.

DESIGN FOR A FONT OF PRINTING-TYPE.

SPECIFICATION forming part of Design No. 20,690, dated April 28, 1891.

Application filed March 5, 1891. Serial No. 383,912. Term of patent 7 years.

To all whom it may concern:

Be it known that I, HENRY BREHMER, a citizen of the United States, residing at 2359 First avenue, in the city of New York, county 5 of New York, and State of New York, have invented and produced a new and original Design for a Font of Type; and I do declare the following to be a full, clear, and exact description of the same, reference being had to the accompanying impression, forming a part thereof.

This design consists of a font of type composed of upper and lower case letters, figures, and parts; and it has for its leading features 15 letters and figures of height and width about the same and having slender standards or stems of uniform width, having wedge-shaped terminals with their bases outward.

The letter A has two wedges at the top, and 20 its lower ends have the bases of the wedges at an angle to each other, and its cross-bar is formed with a reverse curve. The middle bars of the letters E and F are longer than the others. The letter G terminates in a bar 25 turning suddenly inward. The cross-bar of the letter H is made with a reverse curve.

The two outside bars of the M and W are much longer than the two inside ones. The middle bar of the letter N is made with a reverse curve. The top wedges of the X and 30 Y are at an angle to each other.

The top of the 4 is open and the wedge is thereat. The top of the 8 is flat, and the & is composed of a curve and straight lines, the last terminating in the wedges. The a has a 35 flat curved top. The bottom of the loop of the b comes to an angle, and the same is true of the p and q. The middle of the e is made with a reverse curve. The g has its dash crossing the loop, and the tail starts on a straight 40 line and then curves. The h, m, n, and s go below the line in the u above. e, o, v, w, x, and z are like the same capitals.

What I claim is—

The design for the font of type, substantially as described and shown. 45

In testimony whereof I affix my signature in presence of two witnesses.

HENRY BREHMER.
